UNITED STATES PATENT OFFICE

2,369,365

DOUBLE-ACTION PUMP

Floyd A. Nichols, San Rafael, Calif., assignor of
fifty per cent to Tyrrell A. S. Berger

Original application September 8, 1943, Serial No.
501,568. Divided and this application July 29,
1944, Serial No. 547,169

1 Claim. (Cl. 103—47)

The present invention appertains to new and useful improvements in double action pumps, the same being a division of my co-pending application Serial No. 501,568, filed September 8, 1943.

An important object of the present invention is to provide a pump of the double action type, operated by fluid pressure and adapted to have a lifting power considerably greater than pumps of the same capacity and such as are in general use today.

Various other important objects and advantages of the invention will become apparent to the reader of the following description.

In the drawings:

Figure 1 is a side elevational view of the pump.

Figure 2 is an end elevational view.

Figure 3 is a vertical sectional view through the apparatus.

Figure 4 is an enlarged sectional view through the automatic valve of the apparatus.

Referring to the drawings wherein like numerals designate like parts, it can be seen that the structure, as clearly shown in Figure 3 consists of a pressure cylinder 45 and a pump cylinder 46, the cylinder 45 having a pair of pistons 47, 47 therein, connected by a piston rod 48 having a rack 49, which meshes with a gear 50, the latter, in turn, meshing with a gear 51 which, in turn, meshes with a gear 52. The gear 52 meshes with a rack 53 located on a piston rod 54 which connects a pair of pistons 55, 55 in the pump cylinder 46.

A suitable roller guide 56 is provided for the piston rod 54.

The ends of the cylinder 46 are connected by pipes 57, 58, the same being provided at their ends with valves 59 and 60, respectively, the same being respectively exhaust and intake valves. Pipes 61, 62 extend from these pipes 57, 58 to a well or other source of liquid to be moved.

An automatic valve generally referred to by

numeral 63 is employed in conjunction with the cylinder 45 and is constructed as follows. A case (see Figure 4) is denoted by the numeral 29, and has ports 30, 31, 32, 33 and 34. Inside of the case 29 is an oscillatory element 35 having a tapered portion 36. The exhaust or return ports 30 and 34 are in communication with a connecting pipe 37 which, in turn, is connected by a pipe 38 to the sump. The port 31 is connected by a pipe 39 to one side of the pressure cylinder 45, while the port 33 is connected by a pipe 40 to the other side of the cylinder 45. A pressure line 11 communicates with the valve 63 at the port 32. The valve element 35 is controlled by an arm 41a which extends downwardly adjacent the gear 50, and which is adapted to be moved by pins 65 and 66 carried by the gear.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

25 A pump apparatus comprising a fluid pressure circuit including a pump, a double acting pump cylinder, and a double acting pressure cylinder operated by the pressure circuit and operatively connected with the double acting pump cylinder, an automatic valve for controlling the supply of fluid pressure from the circuit to the pressure cylinder, an operative connection between the pressure cylinder and the pump cylinder, said connection being adapted to operate said valve, said connection consisting of a train of gears, said automatic valve having an arm and pins on one of the gears for engaging the arm and actuating the valve.
